C. TWEEDIE

OVERGAITER

Filed July 11, 1927

UNITED STATES PATENT OFFICE.

CHARLES TWEEDIE, OF JEFFERSON CITY, MISSOURI.

OVERGAITER.

Application filed July 11, 1927. Serial No. 204,767.

My invention relates to overgaiters and has for its principal object to devise an overgaiter that will fit properly and present a good appearance. It consists principally in the arrangement and combination of parts hereinafter described and claimed.

In the accompanying drawing wherein like numerals refer to like parts wherever they occur,

10 Fig. 1 is a diagrammatic view in longitudinal elevation showing my overgaiter in full lines in comparison with a standard shoe pattern indicated in dotted lines,

15 Figs. 2 and 3 are, respectively, views of the inner side and of the outer side of my overgaiter applied to a shoe which is indicated in dotted line, and

20 Figs. 4, 5, 6 and 7 are, respectively, detail views of the inner quarter, the button fly quarter, the button quarter, and the shank strap.

An ordinary overgaiter of the present day has the following, among other disadvantages: namely; It does not hug the shoe 25 tightly enough but gaps and flops around in an unsatisfactory way; its front seam does not stay in proper position but very frequently goes awry and presents a bad appearance; the fastening strap is usually so 30 arranged that the overgaiter has to be dragged or pulled over the foot and is thereby likely to be soiled; and such mounting of the strap makes it unnecessarily difficult for corpulent people to put on such overgaiter.

35 My overgaiter, which is made of woven fabric, comprises an inner quarter 1, a button quarter 2, a button hole or fly quarter 3, and a strap 4. The rear edges of the inner and button quarters are sewed together forming 40 the rear seam; and the front edges of the inner quarter and of the button fly are sewed together, forming the front seam. The strap is secured to the lower edge of the button quarter and is extended in the line of the buttons and preferably extends from the 45 top of the button quarter a sufficient distance beyond the lower edges of said button quarter to pass below the shoe shank and reach a tab 5 on the lower margin of the inner quarter. The tab has a button hole 6 and the end portion of the strap has a button 50 7 that engages therewith.

55 My invention may be better understood by comparison with a standard shoe pattern 8 of upper for men's button shoe. The out-

line of such a pattern is indicated in dotted lines in Fig. 1. The shape and dimensions of the top portions of the quarters of my overgaiter are the same as those of the standard pattern. According to the present invention, 60 however, the lower portions of both the front and the rear seams of my overgaiter are sprung in; that is, the front and back edges of the lower portions of the quarters are "cut scant". By this arrangement, the edges of 65 the upper portions of the quarters coincide with those of the standard pattern; but at the bottom edges, the quarters of my device lack about three-sixteenths of an inch at the rear of reaching the rear edge of the standard pattern, and at the bottom of the front edge, my quarters lack about a half inch or more, of reaching the front edges of the standard pattern. The point A at which the front edge of my quarters begins to depart 70 from the edge of the standard pattern is located about the center of the ankle throat curve of the standard pattern; and from this point downwardly the front edge of my quarters follows a substantially straight line 75 to and slightly beyond the vamp line point B of the standard pattern, and from the end of this line, which is near the lower margin of this quarter, the seam is sprung in even more. The point C at which the rear edge 80 of my quarters depart from the rear edge of the standard pattern is located about opposite the point A. The effect of thus 85 springing the front and rear seams, coupled with the use of the strap and the flexibility 90 of the material is to make the lower edge of the overgaiter hug the shoe nicely throughout all movements of the foot.

95 Overgaiters of the type commonly in use have their buttons arranged in a vertical line; and the strap is secured to the button hole fly with its ends about equidistant from the back of the shoe. According to the present invention, the line of the buttons is not vertical but inclines upwardly and rearwardly at an angle of about seventy-two degrees more or less. The strap is preferably permanently secured to the button quarter at the front edge thereof and extends in the line of the seam; and the inner quarter has a tab or extension along its bottom margin that is provided with a button hole for the button on the end of the strap. This button hole is located forwardly of the button strap in the position that the button 105 110

on the strap will naturally occupy when the strap, is wrapped around the shank of the shoe and bears flatwise against said shank.

The effect of this arrangement of the strap coupled with the springing of the seams and the flexibility of the material is to induce stresses that tend to hold the front seam in the proper position on the shoe and to pull it back to its proper position in case it has been set awry. Another advantage of this arrangement is that the strap button, being on the inner side of the foot can be easily reached for buttoning or unbuttoning; and as the strap is secured to the button quarter the overgaiter may be mounted by wrapping it around the foot as distinguished from pulling it over the foot. The gaiter may be readily put on or taken off of the foot without unbuttoning the strap and without danger of soiling the overgaiter, because it is only necessary to insert the heel portion of the shoe between the back of the overgaiter and the strap, and then wrap the gaiter around the foot and button the same. Accordingly, it is not essential that either end of the strap be detachably fastened, but either or both ends may be either permanently or detachably fastened, either by buttons or any other suitable fastening device.

30 30 What I claim is:

1. An overgaiter comprising an inner quarter, a button quarter secured to said inner quarter by a rear seam, a button hole quarter secured to the inner quarter by a front seam, and a strap permanently secured to the button quarter and detachably secured to the inner quarter at a point forward of its point of attachment to the button quarter.

40 2. An overgaiter comprising an inner quarter, a button quarter secured to said inner quarter by a rear seam, a button hole quarter secured to the inner quarter by a front seam, and a strap connecting the button quarter and the inner quarter, its attachment to the inner quarter being at a

point forward of its point of attachment to the button quarter.

3. An overgaiter comprising an inner quarter, a button quarter secured to said inner quarter by a rear seam, a button hole quarter secured to the inner quarter by a front seam, and a strap adapted to extend under the shank of a shoe and connect the lower portions of the inner quarter and the button quarter, said strap being permanently secured to the button quarter and extending downwardly and forwardly therefrom so as to reach the inner quarter at a point forward of its point of attachment to the button quarter when wrapped flatwise against said shoe shank.

4. An overgaiter comprising an inner quarter, a button quarter secured to said inner quarter by a rear seam, a button hole quarter secured to the inner quarter by a front seam, and a strap adapted to extend under the shank of a shoe and connect the lower portions of the inner quarter and the button quarter, the line of buttons sloping upwardly and backwardly, and said strap being secured to the button quarter and extending downwardly and forwardly therefrom so as to reach the inner quarter at a point forward of its point of attachment to the button quarter when wrapped flatwise around said shoe shank.

5. A woven fabric overgaiter comprising an inner quarter, a button quarter secured to said inner quarter by a rear seam whose lower portion is sprung inwardly, a button hole quarter secured to the inner quarter by a front seam whose lower portion is sprung inwardly, and a straight strap permanently secured to the button quarter and extending downwardly and forwardly and detachably secured to the inner quarter at a point forward of its point of attachment to the button quarter.

Signed at Jefferson City, Missouri, this 90 first day of July, 1927.

CHARLES TWEEDIE.
